[57] CLAIM

The ornamental design for a combined bathtub and shower fixture unit, substantially as shown and described.

DESCRIPTION

FIG. 1 is a perspective view of a combination bath and shower head embodying our new design.

FIG. 2 is a front elevational view thereof; and

FIG. 3 is an elevational view as seen from either side thereof.

The broken line representation of a portion of a bathroom wall in FIGS. 1 through 3 is for the purpose of illustration only.

FIG. 1

FIG. 2
